G. F. VOIGHT

WIRE FASTENER

Filed Dec. 31, 1925

INVENTOR -
George F. Voight

UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

WIRE FASTENER.

Application filed December 31, 1925. Serial No. 78,587.

My invention relates to improvements in wire fasteners particularly adapted for attaching wire lath in outstanding order to the wall sheathing of stucco structures, although also useful for other purposes.

One of the objects of the present invention is to provide a wire fastener in which a spacing element is carried on a driven element and operatively moved therealong for cooperation therewith for engaging and attaching wire lath to the wall sheathing of a structure outstanding therefrom as above mentioned.

A further object is the provision of a wire fastener of the character described, in which the driven element is in the form of a nail having the usual cylindrical shank having at its upper end a flat head and intermediate its ends lateral projections adapted to engage the spacing element for limiting its movement on the shank longitudinally of the latter.

With the foregoing and still further objects and purposes in view which will appear as the description proceeds, my invention resides in the combination and arrangement of parts and in the details of construction hereinafter described and claimed, it being understood that changes in the precise embodiment of the invention herein described can be made within the scope of what is claimed without departing from the spirit of the invention.

In the accompanying drawings—

Figure 1 is a view in elevation of a wire fastener constructed in accordance with my invention, disposed in driving position against a fragmental portion of the wall sheathing, and a cross sectional view of a portion of the wire lath supported thereby;

Figure 2 is a view in elevation of the fastener in its final position as driven in the wall sheathing, the latter shown in vertical section, and a portion of the wire lath confined between the nail head and the spacing element;

Figure 3 is a vertical sectional view of the spacing element and upper portion of the driven element, attached to the wall sheathing, with a portion of the wire lath confined between portions of said elements, and a section of the stucco composition applied thereto;

Figure 4 is a view in elevation of one side

of the lower portion of the driven element;

Figure 5 is a view on line 5'-5' of Fig. 1; with an intermediate portion of the wire lath broken away;

Figure 6 is a view on line 6'-6' of Fig. 2;

Figure 7 is another side elevation of the lower portion of the driven element;

Figure 8 is a view on line 8'-8' of Fig. 7;

Figure 9 is a median vertical sectional view of the spacing element;

Figure 10 is a median vertical sectional view of the lower portion of the driven element; and

Figure 11 is a perspective view of that portion of the spacing element shown in Fig. 9.

Figures 4, 5, 6, 7, 8, 9, 10 and 11, are drawn on a larger scale than Figures 1, 2 and 3.

Referring to the drawings in detail, throughout which like reference characters designate like parts:

The numeral 1 designates the wall sheathing of a stucco structure, which sheathing comprises, preferably, boards of equal thicknesses nailed in close-jointed order across the face of the studding and other frame timbers comprising the frame work of the exterior walls of the structure, to receive a stucco covering.

To the face of the wall sheathing 1 is preferably applied a covering of building paper 2, which is intended to preclude moisture penetrating the stucco composition 3 from penetrating to the wood work of the structure.

Inasmuch as the building paper 2 may be considered to form a part of the wall sheathing against which the stucco composition is spread, the designation, "wall sheathing" or "sheathing", when the same hereinafter appears, is intended to include the building paper.

4 designates the spacing element, and 5 the driven element, of my improved fastener.

The spacing element 4, which is of fibrous composition, is preferably formed by stamping it out of sheets of carton-board, fibre-board, card-board, or the like, of suitable thickness, and is preferably cylindrical in cross section with upper and lower flat sides and has a central opening 6 extending through from one of said flat sides to the other flat side, and a pair of grooves or channels 7 which also extend through

from the upper to the lower side thereof and intersect with said opening on opposite sides thereof.

The driven element 5 comprises preferably a nail having the conventional cylindrical shank 8 provided at its upper end with a flat head 9 and intermediate its ends with an upper and a lower pair of lateral projections 10 and 11 respectively.

10 The projections 10 and 11 are preferably formed by pressing indentations 12 and 13 into the sides of the shank 8.

15 The spacing element 4 is preferably "factory assembled" on the shank 8, and is preferably disposed thereon by projecting the forward end of the shank including the lower projections 11, through the opening 6 from the upper end of the block.

20 The spacing element 4, which is adapted to be carried on the shank 8 between the projections 10 and 11, and which is preferably free to rotate relative to the shank, is normally limited in its vertical movement thereon in either direction, by means of said 25 projections, of which the upper projections 10 are engageable with the upper side of the spacing element for limiting its movement upwardly, and the projections 11 engageable with the lower side thereof for limiting its 30 movement in a downwardly direction, relative to the shank.

35 The spacing element 4 is adapted primarily for holding the wire lath 14 a distance outwardly from the wall sheathing 1, and the driven element 5 is adapted for binding the wire lath against the upper side of the spacing element and for binding the latter against the wall sheathing.

40 To apply the present wire fastener for attaching the wire lath to the wall sheathing, the forward end thereof including the spacing element, is projected through one of the interstices of the lath and manipulated to bring one side of the shank 8, above 45 the spacing element, into engagement with one of the wires of said interstice and the point of the shank bearing against the wall sheathing (see Fig. 1). The shank is then driven forward through the spacing element 50 into the wall sheathing until the head 9 engages and binds the wire lath firmly against the spacing element and the latter against the wall sheathing (see Fig. 2).

55 The fasteners may be disposed at such intervals along the wall sheathing as found best suited for the work to be performed. I have found that spacing them about eight inches apart is quite ample for attaching the general type of wire lath used in stucco construction work, including the wire lath commonly known as "poultry wire".

60 The stucco composition is preferably applied by spreading it on the wall sheathing and on and around the wire lath and the 65 exposed portion of the fasteners.

In order to avoid absorption of moisture by the spacing element, I impregnate them with paraffine, preferably by immersion in heat molten paraffine wax, which may be done either after or before assembling the 70 spacing element on the driven element, or, if preferred, the fibre sheets from which the spacing elements are cut may be suitably treated with paraffine.

75 While the opening 6 is preferably made large enough to permit of free passage therethrough of the shank 8, it is intended that the lateral projections 10 and 11 should project far enough outwardly from the side of the shank to extend beyond the margin of the opening so as to engage the upper and lower sides of the spacing element when the latter is moved upwardly or downwardly, respectively, relative to the driven element, and thereby normally limit its 80 movement in said directions.

85 As the most practicable method of forming the lateral projections 10 and 11, is by pinching the shank from opposite sides between suitable dies to force portions of the 90 metal forming the shank outwardly from the sides thereof, and as such work of pinching the shank is best performed during the forming of the nail by equipping the nail-making machine with suitable dies, it is preferable to assemble the spacing element on the driven element after the projections have been formed, which may be done by forcing the forward end of the shank and the lower projections 11 through from the 95 upper end of the opening 6 until said projections 11 clear the lower end thereof and the spacing element is disposed between the upper and lower divisions of said projections (see Fig. 1). The projections 11 extend 100 outwardly beyond the margin of the opening 6. Forcing them therethrough causes them therefore to engage the upper side of the spacing element adjacent the opening and to tear their way therethrough thereby 105 forming the grooves 7 on opposite sides of the opening. These grooves on account of the fibrous composition of the spacing element, will be found to partly close up following their forming, which closing up prevents accidental returning therethrough of the projections during the handling of the fasteners as when packing them in containers or removing them therefrom or in handling 110 them for attaching them to the wall sheathing or the like. When the driven element is projected in the wall sheathing for attaching the fastener thereagainst, the upper projections 10 are caused to engage and force their way through the spacing element in the same 115 manner as did the lower projections when the spacing element was assembled on the driven element.

120 If preferred, the grooves or channels 7 may be formed at the time of forming the 125

opening 6, prior to assembling of the fastener, in which case the projections 11 would be passed through said grooves or channels in disposing the spacing element on the driven element.

5 The arrows "a", Fig. 7, indicate the directions of relative movements of the dies in pinching the shank 8 for forming the indentations 12 and 13 in forming the projections 10 and 11.

10 I claim:

15 1. A wire fastener comprising, a spacing element formed of fibrous composition and having a cylindrical opening extending therethrough from its upper side to its lower side, and a cooperating nail projecting through said opening from its upper end, said nail having a projection intermediate its ends disposed above said spacing element and engageable therewith for normally resisting movement of said spacing element to the upper end of said nail.

20 2. A wire fastener comprising a spacing element formed of fibrous material and having a hole extending through from the upper to the lower side thereof, and a cooperating nail projecting through said hole from its upper end, said nail having a projection on one side intermediate its 25 ends disposed above said spacing element for normally limiting the upward movement of said spacing element relative to said nail, said projection adapted to form a passage way through said fibrous material along the margin of said hole for passing therethrough when said nail is operatively projected into the wall sheathing against which said spacing element seats.

3. A wire fastener comprising, a spacing element formed of fibrous composition and 40 having a cylindrical opening extending therethrough from its upper side to the lower side, and a co-operating nail projecting through said opening from its upper end, said nail having a projection intermediate its ends disposed above said spacing element and engageable therewith for normally resisting movement of said spacing element to the upper end of said nail, said nail having another projection near its lower end 45 disposed below said spacing element and engageable therewith for normally resisting movement of said spacing element toward the lower end of said nail.

50 4. A wire fastener comprising a spacing element formed of fibrous material and having a hole extending through from the upper to the lower side thereof, and a co-operating nail projecting through said hole from its upper end, said nail having a projection on one side intermediate its ends disposed above said spacing element for normally limiting the upward movement of said spacing element relative to said nail, said projection adapted to form a passageway 55 through said fibrous material along the margin of said hole for passing therethrough when said nail is operatively projected into the wall sheathing against which said spacing element seats, said nail having another 60 projection near its lower end disposed below said spacing element and engageable therewith for normally resisting movement of said spacing element toward the lower end of said nail.

65 GEORGE F. VOIGHT.
